2 SHEETS—SHEET 2.

UNITED STATES PATENT OFFICE.

GEORGE D. HARRAH, OF BUFFALO, NEW YORK, ASSIGNOR TO MULTOPLEX FILING DEVICE COMPANY, OF BUFFALO, NEW YORK, A CORPORATION OF NEW YORK.

FILING DEVICE.

1,416,289.

Specification of Letters Patent. Patented May 16, 1922.

Application filed December 10, 1919. Serial No. 343,735.

To all whom it may concern:

Be it known that I, GEORGE D. HARRAH, a citizen of the United States, residing at Buffalo, in the county of Erie and State of New York, have invented new and useful Improvements in Filing Devices, of which the following is a specification.

This invention relates to filing devices, and more particularly to improvements in spacing means adaptable to filing devices of the so-called vertical type.

The objects of this invention, among others, are to provide spacing devices which are adaptable to containers which, in manufacture, have not been provided with any sort of spacing devices and also to containers which are made with slotted side edges to receive spacers. A further and important object of this invention is to provide a standard spacer which is adaptable to containers of different widths or depths within the ordinary range of sizes, the result of which is very material reduction in cost of manufacture and reduction of made-up stock. Furthermore, as will hereafter be seen, this improvement provides spacers which are very strong and durable. Other and further objects will appear from the following specifications, and the drawings 30 in which,—

Fig. 1 is a plan view of a sheet-metal strip ready for bending to form the tubular portions.

Fig. 2 is a vertical cross-section of a container and my improvement.

Fig. 3 is an enlarged cross-section on the line 3—3 of Fig. 2.

Fig. 4 is a similar view on 4—4 of Fig. 2.

Fig. 5 is a perspective view of a container 40 provided with my improvement, portions thereof being cut away to show the construction.

It will be understood that containers, whether in the form of drawers or otherwise, are practically always provided with a longitudinal groove or depression in the bottom to receive a locking-rod. In the drawings I have shown in Fig. 2 a container made of wood and in Fig. 5 a container 50 made of sheet metal. These are designated respectively as 1 and 1', and the said grooves or depressions are shown respectively at 2 and 2'.

Upon the upper, side edges of the container are metal control strips 5 which are

either integral with a sheet metal container or secured thereto, and which are secured to said edges when the container is made of wood. These strips 5 have inverted T-shaped slots 6 in their inner sides and said slots extend across the horizontal portions of said strips. This construction and means of securing said strips are not made a part of this application excepting in so far as the same enter into the claimed combinations. 60

Secured to the bottoms of the containers are metal strips 7 which have longitudinal slots of the same, or approximately the same, length as the horizontal parts of the slots 6. These strips are secured so that the 70 slots overlap the grooves 2 or 2' for the purpose which will hereafter appear.

I will now describe my improved spacers; and the same will be best understood if described, in part, by the method of construction. Strips of sheet metal 8, as shown in Fig 1, have the cuttings or incisions 9, which, as shown, leave the central portion of the strip intact. These strips are then bent or rolled upwardly, the central portion 75 between the incisions being made elliptical as shown on Fig. 3, and the end portions made cylindrical as shown in Fig. 4. These end portions, designated by 8', are then bent downwardly at right angles with the central portion, and the triangular-shaped portions 10 between the cuttings 9 are bent 80 downwardly and welded or otherwise secured to the main, horizontal portion and the end portions 8'. These triangular-shaped 85 portions thus secured form rigid braces between the adjacent parts.

Wires 11 having their outer ends bent downwardly to engage and hold in the slots 6 have their inner ends flattened, as shown 95 at 11' in Figs. 2 and 3, and slide within the central portion so that the same may be adjusted to fit a container of any width.

A wire 12, having a loop 13 quarter turned to engage in a slot in the metal strip 100 7, has its ends 12' bent upwardly at right angles and these ends fit within the portions 8' and fit sufficiently snugly not to move out of adjustment, but which may be adjusted to fit containers of different depths. 105

The object in having the flattened portions 11' on the wires 11 is to prevent them from turning in the central portion 8 so that their downwardly-bent ends might slip out of the T-slots; but it is to be under- 110

stood that the same may be held against rotation by other known means without departing from the spirit of my invention. Likewise, the wire 12 may be provided with 5 other form of engagement in the strip 7 than the loop 13; but I have shown and described what I consider the best embodiment of my invention.

I claim:

10. 1. In a filing device of the type described, a spacer comprising a horizontal, tubular member, supporting wires movable axially in said tubular member, vertical tubular members rigidly secured to said horizontal member, and a wire having its end portions bent upward at right angles to engage adjustably within said vertical members.
15. 2. A spacer for a filing device of the type described comprising a tubular member with a horizontal part and with vertical parts, supporting wires adjustable in said horizontal part to adapt the spacer to the width of the container, and a wire having a horizontal portion and upturned ends, the latter so 25 adjustable in said vertical parts as to make the spacer adaptable to containers of different depths.
20. 3. A spacer for a filing device of the type described comprising a tubular member formed from a flat strip of sheet metal notched and bent to form a horizontal middle part and depending vertical parts, wires adjustable axially within said middle part and a wire having end portions bent 35 upwardly at right angles to engage frictionally in said vertical parts, thereby to permit adjustment of the spacer to containers of different depths.
30. 4. In a filing device of the type described, a spacer having a horizontal tubular member and vertical tubular members rigid with

each other, said horizontal member being elliptical in cross-section, supporting wires with downwardly bent free ends and inner portions flattened to fit frictionally and adjustably within said horizontal member, and a wire having its end portions bent upwardly and slidably engaging within said vertical members, whereby said spacer may be adapted to containers of different widths or depths.

45

5. In a filing device of the type described, a rectangular spacer having an upper horizontal bar formed of telescopically related, frictionally engaging parts, certain of which afford supporting extensions, and laterally arranged vertical bars depending from the horizontal bar and formed of telescopically related, frictionally engaging parts.

55

6. In a filing device of the type described, a rectangular spacer having an upper horizontal bar provided with supporting extensions and lateral vertical bars depending from the horizontal bar and formed of telescopically related, frictionally engaging parts.

60

7. In a filing device of the type described, a rectangular spacer having an upper horizontal bar formed of telescopically related, frictionally engaging parts, certain of which afford supporting extensions.

70

8. In a filing device of the type described a spacer having extensible laterally directed supporting projections and an extensible downwardly directed movement-limiting projection.

75

9. In a filing device of the type described a skeleton spacer having vertically adjustable elements and having laterally directed and extensible supporting projections.

GEORGE D. HARRAH.
